DESIGN FOR CARPET.

Design No. 7,343, dated March 31, 1874

UNITED STATES PATENT OFFICE.

JOSEPH M. CHRISTIE, OF KIDDERMINSTER, ENGLAND, ASSIGNOR TO LOWELL
MANUFACTURING COMPANY, OF LOWELL, MASSACHUSETTS.

DESIGN FOR CARPET.

Specification forming part of Design No. 7,343, dated March 31, 1874; application filed March 23, 1874.
[Term of Patent 3½ years.]

To all whom it may concern:

Be it known that I, JOSEPH MILLER CHRISTIE, of Kidderminster, England, have invented a new and original Design for Carpets; and I do hereby declare that the following is a full, clear, and exact description thereof, which will enable others skilled in the art to make and use the same, reference being had to the accompanying photographic illustration, forming part of the specification.

I claim as my invention—

The design for carpets, as shown.

JOSEPH MILLER CHRISTIE.

Witnesses:

JAMES ARCH,

WILLIAM G. HOLLOWAY.
